[57] ABSTRACT

The present device provides a means to remove electrostatic charges from one side of a sheet of paper and means to provide a ground plane so that the remaining charges are attracted to the ground plane which causes the sheets of paper to stack without "floating."

6 Claims, 1 Drawing Figure

PATENTED JUL 30 1974

**METHOD AND MEANS FOR REDUCING THE
EFFECT OF ELECTROSTATIC CHARGES ON
PAPER IN A COPYING SYSTEM**

BACKGROUND

When sheets of paper are processed through a copying machine, especially a copying machine that employs a xerography technique, such sheets retain electrostatic charges thereon. When such charged sheets of paper are stacked in the machine, the sheets "float," i.e., they tend to take a relatively long time after they have left the roller means to come to rest on the stacker plate or on the preceding sheet of paper. Floating of course results in jamming and erroneous sequencing of the sheets of paper being stacked and is very undesirable.

In the past various schemes have been employed to discharge such sheets of paper. Christmas tree tinsel has been hung in proximity to the path of the sheets of paper to wipe the sheets and thus discharge the paper. In another effort the sheets are passed through a discharge station whereat the sheets are subject to a large electrostatic field. If the paper has sufficient moisture the electrostatic field will cause the charges to pass through the paper and thus neutralize one another. However if the paper does not have sufficient moisture such as in the winter time when the air in a building is dried out, the "electrostatic field," discharge technique is not effective.

SUMMARY

The present invention provides a means to deal with sheets of paper under "dry" conditions, i.e., the paper is not sufficiently moist to be discharged by an electrostatic field as described above. In accordance with the present invention the sheets of paper are wiped extensively on the top side as they are transported toward their stacking location. Such a procedure leaves electrical charges on one side of the sheet of paper. As the sheet of paper enters the stacking position it drops to meet a stacking plate. In my invention the stacking plate is made of electrical conducting material (such as good conducting metal) and is connected to ground potential. Accordingly electrical charges gather on the plate (induced by the charges on the paper and of opposite polarity) and attract the sheet toward the plate. The procedure is repeated for each succeeding sheet and thus the sheets of paper are positively drawn toward the plate which results in a satisfactory and desirable stacking procedure.

The objects and features of the present invention will be better understood in connection with the following description studied in conjunction with the drawing.

The drawing is a pictorial schematic of the paper flow showing the charges being wiped and the stacking procedure.

It should be understood that the drawing does not show rollers or belts to transport the sheets of paper through a sorter. Such means of transport are well known and their inclusion in the drawing would only complicate the presentation, especially since it is important to show charges on the sheets of paper. In a like manner there are no means shown for bin selecting in a sorter. Such bin selecting means are well known and the inclusion thereof would also complicate the drawing. The study of the invention should be made with the

idea that proper rollers and bin selecting equipment are employed in the sorter.

Consider the FIGURE in which there is shown a sheet of paper 11 which is a duplication of some document and which has left the copying machine on its way to the stacker. The sheet of paper 11 is shown with positive charges 13 on the upper side thereof and with negative charges 15 on the bottom side thereof. It may be that these charges would be reversed. The charges result from the duplicating process and especially if the duplicating process employs a xerography technique.

Since the sheet 11 is positively driven or carried by rollers (not shown) there are no transport problems resulting from electrostatic charges.

15 The sheet of paper 17 which preceded the sheet 11 is also shown in the drawing. The sheet 17 is carried under a wire brush 19 which is mounted, (by suitable means such as bolts), to a permanent part of the machine (shown by wall 21). The brush 19 in the drawing is shown with an electrically conducting handle which is grounded or connected to ground potential. It should be understood that the ground connection could be made to the wires 23. The wires 28 of course are fabricated from good electrically conducting material such as copper, brass or iron fibers.

20 The brush 19 in the preferred embodiment has a length which is equal to the width of the sheet of paper 17 (or 11) or any sheet of paper passing through the sorter. The wires 28 should be spaced to provide a good 25 wipe of as much of surface of the sheet of paper as possible. The more of the sheet of paper that is wiped, the better are the results. However, the invention will provide improved stacking even if there is not a complete wiping of the charges on the upper side (positive charges in the drawing).

30 As can be seen in the drawing, when the sheet 17 passes in contact with the wires 28 the positive charges conduct through the wires 28 to ground. This procedure is depicted by the missing positive charges on the front end of the upper surface of sheet 17. As the sheet 17 advances further to the left (in the drawing) the positive charges are removed and the sheet emerges from the "wiping" station with only negative charges remaining on its underside. If we examine sheet 25 which preceded sheet 17, we find that the positive charges have been removed completely or virtually completely. In the particular embodiment of the sorter shown in the FIGURE the sheet is turned over so that its under side becomes its top side (as is taking place with sheet 25). It should be understood that the sheets could be fed directly into the stacker in which case the side with the negative charges thereon would be facing the stacker plate. In the sorter embodiment shown in the FIGURE, the sheets are turned over and the remaining negative charges are on the top side of the sheet.

35 If we consider sheet 27, which is the first sheet to enter the stacker, we find that it has come to rest on stacker plate 29. Stack plate 29 is grounded and thus positive charges 31 are induced. The positive charges 31 act to attract the negative charges 33. The negative charges 33 are the remaining charges on sheet 27 and in response to the attraction between positive charges 31 and negative charges 33 the sheet 27 is positively moved toward plate 29. The charges 33 may or may not leak off.

40 As each succeeding sheet approaches the plate 29, more positive charges 31 are induced and the succeed-

ing sheets are positively moved toward the stacker plate. Accordingly, there is no floating and no jamming of sheets in the stacker.

A further benefit results from the arrangement and that is that when the sheets are removed from the stacker bin, if the charges have not leaked off, the sheets will easily separate because the like charges will repel one another.

It should be understood that while I have described my invention with positive charges being removed by the wire brush, the system would work just as easily with negative charges being removed and positive charges remaining. It should be further understood that if the sheets of paper have, for some reason, negative charges on both sides or positive charges on both sides, 15 the system will work as described above.

What is claimed is:

1. A device to be used with a sheet stacking means which is associated with a sheet transport means and wherein sheets to be stacked therein hold electrostatic charges thereon comprising in combination: first electrical conducting means formed to wipe a sheet passing thereunder and disposed along said sheet transport means so as to wipe one surface of a sheet passing therealong; means connecting said first electrical conducting means to a first voltage potential source in order to cause electrical current to flow in response to a sheet being wiped by said first electrical conducting means; means to hold sheets at rest within said stacking means, said means to hold sheets at rest being at least 20 partially formed of electrical conducting material; means connecting said means to hold sheets at rest to a second voltage potential source whereby charges are induced on said means to hold sheets at rest in response to the approach of a sheet which has been wiped by 25 said first electrical conducting means so that the electrostatic attraction between charges remaining on a sheet approaching said means to hold sheets at rest and said induced charges positively urges said sheets

toward said means to hold sheets at rest.

2. A device according to claim 1 wherein said electrical conducting means is a wire brush whose length is substantially the width of sheet passing in contact therewith.

3. A device according to claim 1 wherein said means to hold sheets is a metal plate within said stacker bin.

4. A device according to claim 1 wherein said first voltage potential is ground potential.

5. A device according to claim 1 wherein said second voltage potential is ground potential.

6. A method for reducing the effect of electrostatic charges on sheets of paper which are transported to a stacking location and stacked comprising the steps of:

- a. locating an electrically conducting wiping means in proximity to the sheets of paper carrying electrostatic charges on their respective surfaces;
- b. connecting said electrically conducting wiping means to a voltage potential source whereby electrical charges wiped by said electrical conducting wiping means will conduct therefrom and alternatively be neutralized;
- c. wiping said sheets of paper on one side with said electrically conducting wiping means to cause the electrical charges thereon to conduct therefrom and alternatively be neutralized thereby leaving the electrical charges respectively on the other surfaces of said sheets;
- d. locating an electrically conducting receiving means in said stacking location;
- e. connecting said electrically conducting receiving means to a voltage potential source whereby the charges on the other side of said sheets being stacked act to induce charges on said electrically conducting receiving means to positively pull said sheets toward said electrically conducting receiving means.

[57] ABSTRACT

The present device provides a means to remove electrostatic charges from one side of a sheet of paper and means to provide a ground plane so that the remaining charges are attracted to the ground plane which causes the sheets of paper to stack without "floating."

REEXAMINATION CERTIFICATE
ISSUED UNDER 35 U.S.C. 307THE PATENT IS HEREBY AMENDED AS
INDICATED BELOW.

Matter enclosed in heavy brackets [] appeared in the patent, but has been deleted and is no longer a part of the patent; matter printed in italics indicates additions made to the patent.

ONLY THOSE PARAGRAPHS OF THE
SPECIFICATION AFFECTED BY AMENDMENT
ARE PRINTED HEREIN.

Column 2, line 11:

*Copying machines employing the xerography technique
are also known as electrostatic photocopying machines.*

AS A RESULT OF REEXAMINATION, IT HAS
BEEN DETERMINED THAT:

The patentability of claims 1-6 is confirmed.

New claims 7-22 are added and determined to be patentable.

7. *The method of claim 6 including:*

*copying documents by an electrostatic photocopying
process, to provide said sheets of paper.*

8. *A method as defined in claim 6 in which:*

*said sheets are wiped on their upper surfaces, and are
turned upside down after they are wiped so that when
said sheets approach said electrically conductive re-
ceiving means the wiped side faces said electrically
conductive receiving means.*

9. *The method of claim 6 wherein the top sides of the
sheets are wiped and the top sides of the sheets remain
facing upwardly until stacked.*

10. *The method of claim 6 including the steps of:*

*positioning said electrically conducting receiving means
at an acute angle to the horizontal,
ejecting each of said sheets after it has been wiped, and
stacking the ejected sheets on said electrical conductive
receiving means.*

11. *The method of claim 6 including the steps of:*

*positioning said electrically conductive receiving means
with a portion thereof lower than the remainder,
ejecting at least some of said sheets toward said stacked
sheets with one edge of each sheet leading the remain-
der of the sheet, and*

*stacking the ejected sheets above said electrically con-
ductive receiving means with the leading edge of each
of said sheets lower than the remainder of the sheet
and with said leading edge above said lower portion of
said electrical conductive receiving means.*

12. *The method of claim 6, wherein:*

said sheets are stacked at an angle to the horizontal.

13. *A device according to claim 1 in which said first
electrical conducting means comprises means (a) for wip-
ing only one side of each sheet passing thereunder to re-
move charges primarily from said one side, and (b) for
leaving said remaining charges on the other side.*

14. *A device according to claim 1 having:*

*electrostatic photocopying machine means for producing
said sheets to be stacked.*

15. *In a device according to claim 1:*

*electrostatic photocopying machine means, having said
sheet transport means at its output, for supplying said
sheets to said sheet stacking means.*

16. *In a device according to claim 1:*

*said sheet transport means discharging each of said
sheets toward said means for holding sheets at rest
with one edge of each sheet leading the remainder of
the sheet during each such discharge.*

*said means for holding sheets at rest having a sheet
supporting surface having two ends the first end of
which is adjacent to said transport means and the
second end of which is at a different elevation than
said first end, for stacking said leading edges of said
sheets adjacent to one of said ends of said sheet sup-
porting surface.*

17. *A device according to claim 1 in which said device
comprises means which stacks said sheets with charges
thereon of predominately one polarity so that when the
stacked sheets are removed from the device they tend to
repel each other.*

18. *A device according to claim 1 in which said sheet
transport means includes means for physically discharging
said sheets in a downward direction.*

19. *The method of claim 6 applied to a Xerographic
process.*

20. *The method of claim 6 in which said sheets of paper
are stacked with charges thereon which are predominately
of one polarity so that when the sheets are removed from
said electrically conductive receiving means they tend to
repel each other.*

21. *In a device as defined in claim 1, said device com-
prising means for stacking said sheets at an angle to the
horizontal.*

22. *A device as defined in claim 3 in which said metal
plate is at least as long as the sheet in the direction that the
sheet moves as it approaches the metal plate.*
